UNITED STATES PATENT OFFICE.

CHARLES N. COX, OF BROCKMAN, CALIFORNIA.

DIRIGIBLE HEADLIGHT.

1,216,216.

Specification of Letters Patent. Patented Feb. 13, 1917.

Application filed September 20, 1916. Serial No. 121,368.

To all whom it may concern:

Be it known that I, CHARLES N. COX, a citizen of the United States, residing at Brockman, in the county of Lassen and State of California, have invented new and useful Improvements in Dirigible Headlights, of which the following is a specification.

This invention relates to automatic head lamp controls, the object in view being to provide simple means applicable to any motor vehicle either at the time of manufacture or subsequent thereto, whereby one or more lamps are so controlled by the steering mechanism hereinafter described, that said lamp or lamps are automatically turned to the right or to the left in accordance with the direction or angles assumed by the steering wheels of the machine.

One of the principal objects of the present invention is to provide simple means whereby the lamp turning mechanism may be readily adapted to different makes of machines and whereby also the lamp or lamps may be caused to turn at equal angles with the steering wheels or at greater or less angles. By reason of the arrangement hereinafter described, the rays of light from the lamp or lamps are directed upon the road-way in accordance with the direction taken by the machine instead of being directed continuously straight ahead in line with the longitudinal axis of the vehicle as is now the case.

With the above and other objects in view, the invention consists in the novel construction, combination and arrangement, herein fully described, illustrated and claimed.

40 In the accompanying drawings:

Figure 1 is a plan view of a sufficient portion of the under structure of a motor vehicle to illustrate the present invention in its applied relation thereto.

45 Fig. 2 is a vertical longitudinal section through the same.

Fig. 3 is a side elevation of the lamp turning mechanism.

50 Fig. 4 is a vertical longitudinal section through the same.

Fig. 5 is a vertical cross section through the same.

Fig. 6 is a fragmentary horizontal section taken just above the lamp turning arm.

55 Fig. 7 is a top plan view of the supporting bracket and stop plate.

Fig. 8 is a plan view similar to Fig. 1 showing the lamp turning mechanism used in connection with another arrangement of steering gear.

Fig. 9 is a vertical longitudinal section through the same.

Fig. 10 is a plan view illustrating the mechanism as applied to two headlamps.

Referring to the drawings, 1 designates the front axle of a motor vehicle of the present day type, 2 the steering knuckles, 3 the wheel spindles extending from the knuckles, 4 the knuckle arms, and 5 connecting rod of the steering gear which rod is pivotally connected at its opposite ends to the knuckle arms 4. All of the parts thus far described are of the usual well known construction and arrangement. In Figs. 1 and 2, the lamp turning mechanism is shown applied to a vehicle in which the connecting rod 5 is located in rear of the front axle 1. In carrying out the invention, supporting lugs 6 extend upwardly from and are fixedly secured to the connecting rod 5. These lugs are preferably shaped so that they may be clamped tightly upon the connecting rod 5 in order to adapt the mechanism to be applied to a motor vehicle already in use. Extending in a direction generally perpendicular to the connecting rod 5, is a primary motion transmitting member A which, in the preferred embodiment of the invention, is of triangular formation, the same comprising a bar 7 parallel to the connecting rod 5 and formed at its opposite extremities with pintles 8 which are journaled in openings in the lugs 6. The primary motion transmitting member A also comprises side bars 9 which converge from the bar 7 toward their opposite ends where they are secured together by a U-shaped connecting piece 10 embodying upwardly extending ears 11 which project above the member A and carry a guide bracket support or base 12, the latter being supported in relation to the ears 11 by means of a horizontally disposed pin 13 forming a pivotal connection between the motion transmitting member A and the block or base 12.

100 Superimposed upon the member 12 is a guide bracket designated generally at B and shown as consisting of a bottom plate 14, and a top plate 15, said plates being secured together in fixed relation to each other and having interposed between them one or more anti-friction guide rollers 16 having grooved

peripheries to receive and guide the secondary motion transmitting member 17, the latter being shown in the form of a rod which is slideable through guide openings 18 at the front and rear of the guide bracket. The bracket is connected to the base or supporting member 12 by a substantially vertical pivot 19, thereby adapting said bracket to turn on a vertical axis or at a right angle to the axis on which the member 12 turns.

Projecting from one end of the member 12 is a spring or resilient tongue 20 the end portion of which is received in a notch 21 in a down-turned flange 22 of the guide bracket B, said spring tongue serving to hold the guide bracket B in a normally central position while allowing the same to yield in order that the guide bracket may be turned on its pivotal connection with the member 12.

The secondary motion transmitting member or rod is formed at one extremity with an eye or hole 23 to receive a combined pivot and set screw 24 which extends therethrough and through a radial opening 25 in a clamp 26 which surrounds a lamp turning arm 27 connected with the lamp post, whereby the point of pivotal connection between the secondary motion transmitting member or rod and the lamp turning arm 27 may be increased or diminished for the purpose of giving greater or less throw to said lamp turning arm and correspondingly regulating the amplitude of movement of the lamp and the post by which the lamp is carried. The lamp 28 is mounted upon the upper end of a post 29, the latter being supported and journaled in ball bearings 30 in a bracket 31 fastened to the front end of the body of the vehicle as for example, the radiator or the sub-frame which supports the radiator. The bracket 31 carries an arcuate stop plate 32 formed with a longitudinal slot 33 which receives adjustable stops 35 serving to limit the movement of an arm 34 extending from the lamp post. The stops 35 limit the turning movement of the lamp in both directions irrespective of the angle to which the steering wheels are turned. The spring tongue connection between the member 12 and the guide bracket 3 allows for this difference in the movement of the steering wheels and the lamp and thereby prevents injury to the lamp turning mechanism in case the steering wheels are turned to a greater angle than the lamp. 36 designates a supporting rest or rail for the secondary motion transmitting member.

In Figs. 8 and 9, I have illustrated the mechanism as applied to a connecting rod which is located in advance of the front axle, the construction being identical with that hereinabove described with the exception that the lamp turning arm 27 is reversed or set to extend in the opposite direction. In

order to provide for this, the lamp turning arm 27 is formed as illustrated in Fig. 6, the same comprising a split band or collar 37 at one end, the extremities of which are connected by a clamping bolt 38 enabling the arm to be firmly clamped around the lower end of the lamp post 29. In order to prevent slippage, the band or collar 37 is provided on its inner face with a stud or projection 39 which is adapted to enter either one of a pair of diametrically opposite notches in the post 29.

In Fig. 10, the principle of the invention is shown applied to a vehicle employing a pair of head lamps 41 arranged at opposite sides of the radiator or body of the machine, the lamp turning arms 27' being coupled together by a connecting rod 42 so as to cause both of the lamps 41 to turn simultaneously and equally in the same direction. Under the arrangement shown in Fig. 10, the secondary motion transmitting member 43 is attached to the connecting rod 42 and passes through the guide bracket B' carried by the primary motion transmitting member A' in the same relation as hereinabove described.

From the foregoing description taken in connection with the accompanying drawings it will now be understood that as the connecting rod 5 is moved in a substantially longitudinal direction, a corresponding movement is imparted to the primary motion transmitting member A and thereby to the base or supporting member 12 and the guide bracket B. A corresponding movement is also imparted to the secondary motion transmitting member which in turn acts on the lamp turning arm to turn the lamp post and lamp at the same time to a greater or less angle than the steering wheels. It will also be seen that the extent of turning movement of the lamp is regulated by varying the distance between the vertical axis of the lamp post and the point of connection between the lamp turning arm and the secondary motion transmitting member. In view of the fact that the primary motion transmitting member is adapted to rock on a horizontal axis, all relative up and down movement between the body and front axle of the machine is compensated for. The mechanism is adapted for the control of either a single lamp or a plurality of lamps arranged at the front of the machine as hereinabove described and as illustrated in the accompanying drawings.

It is preferred to use rubber or fiber washers in connection with the ball bearings and also in connection with the pintles of the primary motion transmitting member in order to render the mechanism noiseless and prevent rattling.

It will of course be understood that the mechanism hereinabove described is suscep-

tible to changes in the form, proportion and minor details of construction which may accordingly be resorted to without departing from the principle or sacrificing any of the advantages of the invention.

I claim:

1. Automatic lamp control, embodying in combination with a lamp and lamp supporting post adapted to turn on a substantially vertical axis, and the knuckle arm connecting rod of a motor vehicle, a primary motion transmitting member connected with and carried by said connecting rod and mounted to oscillate on a substantially horizontal axis, a secondary motion transmitting member, a guide bracket for the last named member having a pivotal connection with the primary motion transmitting member, a lamp turning arm projecting from said lamp post and a jointed connection between said secondary motion transmitting member and the lamp turning arm.
2. Automatic lamp control, embodying in combination with a lamp and lamp supporting post adapted to turn on a substantially vertical axis, and the knuckle arm connecting rod of a motor vehicle, a primary motion transmitting member connected with and carried by said connecting rod and mounted to oscillate on a substantially horizontal axis, a secondary motion transmitting member, a guide bracket for the last named member having a pivotal connection with the primary motion transmitting member, a lamp turning arm projecting from said lamp post, a jointed connection between said secondary motion transmitting member and the lamp turning arm, said secondary motion transmitting member having a longitudinal sliding relation to said guide bracket.
3. Automatic lamp control, embodying in combination with a lamp and lamp supporting post adapted to turn on a substantially vertical axis, and the knuckle arm connecting rod of a motor vehicle, a primary motion transmitting member connected with and carried by said connecting rod and mounted to oscillate on a substantially horizontal axis, a secondary motion transmitting member, a guide bracket for the last named member having a pivotal connection with the primary motion transmitting member, a lamp turning arm projecting from said lamp post and a jointed connection between said secondary motion transmitting member and the lamp turning arm, said guide bracket having a universal connection with the primary motion transmitting member.
4. Automatic lamp control, embodying in combination with a lamp and lamp supporting post adapted to turn on a substantially vertical axis, and the knuckle arm connecting rod of a motor vehicle, a primary motion

transmitting member connected with 65 and carried by said connecting rod and mounted to oscillate on a substantially horizontal axis, a secondary motion transmitting member, a guide bracket for the last named member having a pivotal connection with 70 the primary motion transmitting member, a lamp turning arm projecting from said lamp post, a jointed connection between said secondary motion transmitting member and the lamp turning arm, said guide bracket having 75 a universal connection with the primary motion transmitting member, and means for yieldingly sustaining said guide bracket in a certain relation to the primary motion transmitting member.

5. Automatic lamp control, embodying in combination with a lamp and lamp supporting post adapted to turn on a substantially vertical axis, and the knuckle arm connecting rod of a motor vehicle, a primary motion 85 transmitting member connected with and carried by said connecting rod and mounted to oscillate on a substantially horizontal axis, a secondary motion transmitting member, a guide bracket for the last named member having a pivotal connection with the primary motion transmitting member, a lamp turning arm projecting from said lamp post and a jointed connection between said secondary motion transmitting member and the 90 lamp turning arm, the connecting means between the secondary motion transmitting member and the lamp turning arm embodying a connecting device which is adjustable on the lamp turning arm toward and away 100 from the axis of the lamp supporting post.

6. Automatic lamp control, embodying in combination with the knuckle arm connecting rod, a head lamp, a supporting post for said lamp adapted to turn on substantially 105 vertical axis, a lamp turning arm projecting from said post, a primary motion transmitting member carried by said connecting rod and having a horizontal pivotal connection therewith, a guide bracket support pivotally connected to said motion transmitting member on a horizontal axis, a guide bracket pivotally connected to said support on a vertical axis, a secondary motion transmitting member carried by and slidably in relation 110 to said guide bracket, and a pivotal connection between said secondary motion transmitting member and lamp turning arm.

7. Automatic lamp control, embodying in combination with the knuckle arm connecting rod, a head lamp, a supporting post for said lamp adapted to turn on a substantially vertical axis, a lamp turning arm projecting from said post, a primary motion transmitting member carried by said connecting rod 115 and having a horizontal pivotal connection therewith, a guide bracket support pivotally connected to said motion transmitting mem-

ber on a horizontal axis, a guide bracket pivotally connected to said support on a vertical axis, a secondary motion transmitting member carried by and slideable in relation to said guide bracket, a pivotal connection between said secondary motion transmitting member and lamp turning arm, means for

yieldingly resisting the movement of said guide bracket on its vertical pivot, and adjustable stop mechanism for limiting the turning movement of the lamp irrespective of the angles to which the steering wheels are turned.

CHARLES N. COX.
